(57) CLAIM

The ornamental design for a pavilion, as shown and described.

DESCRIPTION

FIG. 1 is a perspective view of a pavilion showing my new design;

FIG. 2 is a front elevational view thereof, the right side, left side, and rear side views being the same;

FIG. 3 is a top plan view thereof;

FIG. 4 is a perspective view thereof, shown with the doors open;

FIG. 5 is a front elevational view thereof, shown with the doors open, the right side, left side, and rear side views being the same; and,

FIG. 6 is a detail view of the handle portion of the pavilion of FIG. 1.

The broken lines are included for the purpose of illustrating unclaimed portions of the pavilion and form no part of the claimed design.

1 Claim, 6 Drawing Sheets
